Application September 23, 1935, Serial No. 41,791
In Austria October 1, 1934

3 Claims. (CL 124—11)

This invention relates to improvements in machine guns or machine pistols normally operated with explosive propellants and in which a projectile feed mechanism is attached to and in communication with the barrel of the gun and a compressed air supply control mechanism is fitted in the casing of the gun in place of the normal breech mechanism.

The essential feature of the present invention consists in the provision of a push rod extending into and sliding in the barrel of the gun, an opening in the barrel through which a projectile enters the barrel in front of said push rod, a piston rod connected with and forming the extension of the rear end of said push rod, a piston fixed to said piston rod, a cylinder in the casing of the gun and in which said piston is working, a longitudinal compressed air channel extending through said push rod and said piston rod but terminating in front of said piston and establishing communication between said barrel and the interior of said cylinder in front of said piston, compressed air ports in said cylinder establishing communication between the outside and the inside of said cylinder and controlled by said piston, a compressed air supply tube attached to the casing of the gun and establishing communication with the interior of said cylinder behind the piston, a second piston fixed to said piston rod at the rear of the piston first mentioned and controlling the outlet of said tube, and spring means cooperating with said piston rod and the casing of the gun for returning the piston into its initial position.

In view of the aforesaid it is possible to insert a device for practicing firing by means of compressed air particularly in light machine guns and machine pistols without the necessity of any constructional change to the breech case after the removal of the movable breech parts.

Two modes of carrying out the present invention are illustrated by way of example on the accompanying sheets of drawings in which:

Figure 1 is a side view of a light machine gun mounted on a stand carrying the means for operating the device for the discharge of projectiles by the use of compressed air.

Fig. 2 is a cross section taken on line II—II of Fig. 1.

Fig. 3 is a fragmentary side view of the fastening of the fork-shaped stand.

Fig. 4 illustrates the projectile-feeder in longitudinal section and Fig. 5 in cross section along line V—V of Fig. 4 respectively.

Fig. 6 is a longitudinal section through the

projectile-feeder shown in Figs. 4 and 5. Fig. 7 shows a projectile-feeder of modified construction and in longitudinal section.

As shown in Figs. 1 and 2, the machine gun is provided with the gun stock 1, the breech case 2, the projectile firing device 3, inserted in the case 2 after the removal of the breech-part. The jacket of the gun-barrel 4, rests by means of a shackle 5 on a guide bar 6, which is slidably mounted in a bed 7, carried by the fork-shaped stand 8 of the machine gun. Further the electromotor 9 is mounted on the bed 7 and its driving shaft 10 carries a cam-shaped disc 11, which causes a jerky motion by co-operating with the stops 12 of the slide bar 6. A bevel wheel 13 is mounted on the shaft 10 and meshes with the bevel wheel 14 transmitting the movement of the motor to the projectile firing device 3 by way of the shaft 15, the toothed wheels 16, 17 and the flexible shaft 18. The trigger 19 is provided with two steps or finger grips 20 and 21, the former being for single firing and the latter for uninterrupted firing. According to Figs. 4 and 5, the projectile firing device consists of a cylindric case 22, forming the compressed air compartment 23 and connected by means of tube 24 with a compressed air source or a pressure gas receptacle, which supplies compressed air or compressed gas of about 6 atmospheres. The compressed air compartment 23 is enclosed in an annular guide 25, in which is slidably mounted a slip-ring 26, furnished with recesses 27 for the reception of the projectiles rolling-in from the projectile receptacle 28. This slip-ring has internal air-tight connection with the cylindric wall 29 of the cylindric case 22 and external contact with fitting face 30, provided in the extension 31 of the case 22. The opening 32 provided in the cylindric wall 29 is closed alternately by the solid parts of the slip-ring, and opened for passing compressed air when the recesses 27 slide over the same. The extension 31 fits into the cartridge chamber of the barrel 33 of the machine gun and is provided with a screw-threaded bore, into which may be screwed the insertion barrel 35 of the same calibre as the projectiles to be fired. The flange 36 of the same rests on the jacket of the gun-barrel 4 of the machine gun so that, when screwing-in the insertion barrel 35, the projectile firing device is securely fixed in the barrel and at the same time the barrel is secured in the jacket of the gun-barrel 4. The bore 37 of the insertion barrel is continued through the extension 31 and thus constitutes the barrel-bore. As shown in Fig. 6, 55

the projectile receptacle 28 is adapted to be closed air-tight by a cap 38 and is supplied with compressed air by a small tube 39, so that the projectiles 40 fed into the receptacle, are supplied to the recesses 21 of the slip-ring 26 by the pressure exerted by the compressed air. The slip-ring 26 is rotated by a worm 43 through the agency of the flexible shaft 18. The stepwise rotation can be carried out in a convenient manner 10 by a Maltese cross, a worm with variable pitch or the like. Fastenings 41 and 42 serve for securing the fork-shaped stand.

The outside shape of the cylinder 57 of the constructional example of the projectile feeder 15 shown in Fig. 7 is adapted to conform to the case 55 of the various machine guns in such a manner, that the device can be readily fitted in any type of machine-guns or machine pistols. The cylinder is provided with two bores 72, 73 of different 20 diameters, the larger bore 73 being enlarged at 74 and a sleeve 58 used as guide face is inserted in the same and is perforated at a number of places 76 for the passage of the compressed air from one side of the piston to the other side 25 thereof. Pistons 60 and 61 are mounted on and fixed to the piston rod also acting as projectile feeder. The part of the piston rod 68, disposed in front of the cylinder 57, is reduced to the caliber of the inserted barrel 54 and forms a 30 push-rod, and carries a spring washer 69 against which bears one end of a return compression spring 56. The other bearing is formed by a second spring washer 70, which is adjustably secured to the rear end of the inserted barrel 54 35 by means of a screw thread, the tension of the spring 56 and thus the number of shots being varied by axially adjusting the said spring washer 70. The projectiles, subjected in the tubular projectile receptacle 62 to the pressure 40 of the helical spring 63, pass into the bore of the inserted barrel 54 and come to rest in front of the push rod 77 of the piston rod 68.

The compressed air passes through the tube 67 into the cylindric chamber behind the piston 61 45 and has the tendency to force the same in the direction of firing. The piston 61 cannot move forward because the same is locked by the latch or lever 52 by way of the piston rod 68 and the bracket 71 connected with the rear end thereof. 50 The lock is released and the piston 61 is forced forward when the trigger is pulled. The small piston 60 then closes the port for the admission of the compressed air, while the rear end of the piston 61 opens the hole 78, so that the compressed air passes through the enlarged annular chamber 74 and through the other perforations 76 of the sleeve 58 into the space in front of the piston 61 and, by way of the transverse opening 59 and the axial bore 51 of the piston rod 68, 55 enters the inserted barrel. During the forward movement of the piston 61, its rod 77 pushes a projectile 65 in the inserted barrel 54 and the projectile is hurled out by the compressed air supply. Whenever a shot is fired and the front 60 of the piston 61 is no longer subjected to pressure, the spring 56 forces the piston rod 68 back into its initial position, whereby the push rod 77 clears the bore of the inserted barrel 54, so that the following projectile jumps forward and into 65 the bore. During the return movement of the piston 61, the compressed air supply is again released by the piston 60 and this procedure is repeated during the continuous or uninterrupted firing until the trigger is released and the piston 70 rod is blocked again by the latch or lever 52.

When fitting this device in a heavy machine gun it is only necessary to provide the interposed sliding device with a return spring because the piston-stroke in the compressed air cylinder is sufficient for pushing backward the gun furnished with a sliding device. Therefore the moving parts are preferably of considerable weight. Thus, for instance, the piston and the piston rod may be provided with a core of heavy metal such as lead. 10

What I claim is—

1. In a machine gun or machine pistol normally operated with explosive propellants, a projectile feed mechanism attached to and in communication with the barrel of the gun, a compressed air supply control mechanism fitted in the casing of the gun in place of the normal breech mechanism and comprising a push rod extending into and sliding in the barrel of the gun, an opening in the barrel through which a projectile enters the barrel in front of said push rod, a piston rod connected with and forming an extension of the rear end of said push rod, a piston fixed to said piston rod, a cylinder in the casing of the gun and in which said piston is working, a longitudinal compressed air channel extending through said push rod and said piston rod but terminating in front of said piston and establishing communication between said barrel and the interior of said cylinder in front of said piston, compressed air ports in said cylinder establishing communication between the outside and the inside of said cylinder and controlled by said piston, a compressed air supply tube attached to the casing of the gun and establishing communication with the interior of said cylinder behind the piston, a second piston fixed to said piston rod at the rear of the piston first mentioned and controlling the outlet of said tube, and spring means cooperating with said piston rod and the casing of the gun for returning the piston into its initial position. 30

2. In a machine gun or machine pistol normally operated with explosive propellants, an auxiliary liner of small caliber inserted in the barrel of the gun, a projectile feed mechanism attached to and in communication with the barrel of the gun or pistol, a compressed air supply control mechanism fitted in the casing of the gun in place of the normal breech mechanism and comprising a push rod extending into and sliding in the barrel of the gun, an opening in the barrel through which a projectile enters the barrel in front of said push rod, a piston rod connected with and forming an extension of the rear end of said push rod, a piston fixed to said piston rod, a cylinder in the casing of the gun and in which said piston is working, a longitudinal compressed air channel extending through said push rod and said piston rod but terminating in front of said piston and establishing communication between said barrel and the interior of said cylinder in front of said piston, compressed air ports in said cylinder establishing communication between the outside and the inside of said cylinder and controlled by said piston, a compressed air supply tube attached to the casing of the gun and establishing communication with the interior of said cylinder behind the piston, a second piston fixed to said piston rod at the rear of the piston first mentioned and controlling the outlet of said tube, and spring means cooperating with said piston rod and the casing of the gun for returning the piston into its initial position. 40

3. In a machine gun or machine pistol normally operated with explosive propellants, a projectile feed mechanism attached to and in communication with the barrel of the gun, a compressed air supply control mechanism fitted in the casing of the gun in place of the normal breech mechanism and comprising a push rod extending into and sliding in the barrel of the gun, an opening in the barrel through which a projectile enters the barrel in front of said push rod, a piston rod connected with and forming an extension of the rear end of said push rod, a piston fixed to said piston rod, a cylinder in the casing of the gun and in which said piston is working, a longitudinal compressed air channel extending through said push rod and said piston rod but terminating in front of said piston and establishing communication between said barrel and the interior of said cylinder in front of said piston, compressed air ports in said cylinder establishing communication between the outside and the inside of said cylinder and controlled by said piston, a compressed air supply tube attached to the casing of the gun and establishing communication with the interior of said cylinder behind the piston, a second piston fixed to said piston rod at the rear of the piston first mentioned and controlling the outlet of said tube, and adjustable spring means cooperating with said piston rod and the casing of the gun for returning the piston into its initial position.
